UNITED STATES PATENT OFFICE.

CUBAN ALFRED MONSEES, OF BROWNSVILLE, TEXAS.

SHOE RACK.

Application filed September 27, 1927. Serial No. 222,291.

This invention relates to a shoe rack and aims to provide novel means whereby a number of shoes may be supported in such a way as to insure shoes of certain pairs being held together for the convenience of the user.

An important object of the invention is to provide a device of this character whereby the shoes may be readily and easily positioned and supported without the use of clamps or other devices that would tend to stretch and ruin the shape of the shoe supported thereby.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view illustrating a rack constructed in accordance with the invention as secured to a supporting structure.

Figure 2 is a sectional view through the rack.

Referring to the drawing in detail, the reference character 5 indicates the supporting rod which is formed with right angled extremities 6 having eyes 7 through which suitable securing screws 8 extend for securing the supporting rod to the supporting structure.

Shoe forms indicated at 9 are mounted on

the rod 5, each of which forms includes an elongated member having a transversely disposed opening extending from one edge of the form to the opposite edge thereof, which openings accommodate the rod 5.

As shown, the openings in the forms 9 are arranged in close proximity to one end thereof, so that each form will include a long end and a short end, with the result that the long ends of the forms will hang 45 downwardly at all times.

In the use of the device, a shoe is positioned over a form in a manner as shown, the short end of the form hanging downwardly, with the result that the weight of 50 the shoe positioned on the form will overbalance the form, causing the shoe to be held against the supporting surface to which the rod is secured, and at the same time providing a form which may be readily and easily 55 disconnected from the shoe in which it is positioned.

I claim:

A shoe rack including a supporting rod, said supporting rod having right angled ends 60 formed with eyes, a plurality of shoe forms having openings to receive the rod, means for supporting the forms in a position to cause the forms to swing inwardly under the weight of shoes positioned thereon, and means extending through the eyes for securing the 65 supporting rod to a supporting surface.

In testimony that I claim the foregoing as my own, I have hereto affixed my signature.

CUBAN ALFRED MONSEES.
